3 Claims. (Cl. 315—39.69)

This invention relates to the construction and operation of electron discharge devices known as magnetrons.

It has been customary in the past to strap alternate segments of the anode structure of such devices in order to "lock" the oscillation in the π -mode since alternate segments in that mode oscillate in phase. For this purpose the strapping has usually been carried out at one or both ends of the anode structure. It is also known to locate the straps within a circumferential groove opening into the anode-cathode space at a point intermediate the ends of the structure. If the anode structure is built up of laminations it is further known to form straps integrally with selected ones of the laminae so that when the laminae are stacked into the usual block form, continuous coaxial straps are distributed, duplicated as required, along the axis of the bore of the anode structure. This disposition of coaxially arranged axially displaced straps for the sake of brevity will hereinafter be referred to as distributed strapping.

While the aforementioned prior art is mainly concerned with the modification and control of the circumferential patterns of the resonant modes, control of the axial patterns by distributed strapping seeks to keep to a minimum the R. F. voltages and currents in the anode for a given power level and to prevent oscillation in modes in which the two ends of the anode structure are in phase opposition.

This invention consists in a non-laminated anode structure in which alternate segments are connected by displaced strapping and in which the faces of the segments facing the cathode present unbroken surfaces.

According to the invention an electric discharge device of the magnetron type having an anode structure comprising a cylindrical yoke member adapted to receive and to have fixed therein a plurality of radially inwardly extending anode segments, said segments each having a plurality of holes positioned transversely of the segment and parallel to the inner edge thereof, the holes being of large and small size in alternate segments and threaded, during manufacture, by straps which contact with the periphery of the smaller holes and are spaced from the periphery of the larger holes so as to connect alternate segments together when assembled in the yoke member.

The invention will be better understood from the following description, reference being had to the accompanying drawing in which Fig. 1 is a voltage curve of a magnetron of the usual type, Fig. 2 is a similar voltage curve of a magnetron constructed according to this invention, Fig. 3 is a plan view and Fig. 4 a sectional elevation on the line X—X in Fig. 3 of our improved magnetron.

Referring first to Fig. 1 this shows a typical curve of voltage between segments along the axial length of the magnetron for a conventional tube with straps at the end faces *a* and *b*. It will be seen that not only is it a poor characteristic because there is considerable variation in voltage along the segments, but the maximum

2

voltage V_1 occurs in the vicinity of the straps, where breakdown is more likely to occur. With the straps distributed along the axial length of the anode at points *c* to *j*, according to this invention the characteristic of the voltage between the segments becomes as shown in Fig. 2. The precise shape of the characteristic will depend on the number and disposition of the straps, but the curve in Fig. 2 is a representative curve for a tube with eight straps disposed equidistantly along the axial length of the anode. The number of straps per unit axial length of anode structure should be as high as possible subject to maintaining clearances from strap to strap or strap to segment, and convenience of construction.

It is obvious that for the same maximum voltage between segments the general voltage level could be raised to the position shown by the dotted curve in Fig. 2 with a corresponding increase in power handling capacity.

One method of constructing a valve according to this invention is illustrated in Figs. 3 and 4. As shown all the segments *K* are made as separate parts, and are drilled to take the straps *m* which may be made up in the form of rings of circular cross section material. Alternate segments will have large clearance holes *n* for the straps to pass through, and the holes along any one segment will be alternately clearance and fitting holes. The segments are then threaded on to the straps *m*, and then fitted into slots in the cylindrical yoke body member *o* before the whole assembly is brazed.

A further advantage of the above method of construction is that the wavelength of the π and π' are separated more widely, so that π' mode is far less liable to be excited and the valve will oscillate more reliably on the correct mode.

The relation between π and π' modes can be understood by considering two separate anodes, formed by splitting a given end strapped anode at its central transverse plane. Apart from small end effects, a half anode has the same π mode wavelength as the whole, since in the π mode there is no current running along the segments across the central plane. If the two half anodes are completely uncoupled they may be excited to oscillate at the same frequency but in any relative phase. For example, they may be in phase (corresponding to the π mode) or in phase opposition (corresponding to the π' mode). When the halves are brought together, the frequency of the π' mode depends on the tightness of coupling (the tighter the coupling the further apart are π and π' modes) as is desirable. In an end strapped tube, axial currents flow to feed the endstrap capacity, and these currents constitute the coupling for the π' mode. They are limited by the inductance in the axial direction of that portion of the segments lying between the straps and the bore, which is approximately proportional to the distance between straps. It is clearly desirable to minimise this distance as for example by putting straps at a point intermediate to the ends of the anode structure, but this would lead to voltage variation. To keep down the axial inductance of the segments it is important to avoid any discontinuity in the segment faces. By our invention a satisfactory way of obtaining both desirable features is achieved simultaneously.

The invention is not in any way to be limited to the particular embodiment illustrated by a "vane" type anode structure in the drawing since any reference to segments hereinbefore shall apply equally to segments which, when assembled in the described manner form anode structures of the types commonly referred to as "hole and slot" or "parallel slot."

What we claim as new and desire to secure by Letters Patent of the United States is:

1. In an electron discharge device of the magnetron type, an anode structure, comprising in combination, a

cylindrical yoke member, a plurality of radially inwardly extending separate anode segments, each of said segments having a passage therein positioned transversely and parallel to the inner edge thereof, said passages being of large and small size in alternate segments and having threaded therethrough a strap contacting the periphery of said small passages and spaced from the periphery of said larger passages, to connect together the alternate assembled segments.

2. In an electron discharge device of the magnetron type, an anode structure, comprising in combination, a cylindrical yoke member, a plurality of radially inwardly extending separate anode segments fixed within said yoke, each of said segments having a plurality of transverse passages positioned parallel to the edge thereof, said passages being of large and small size in alternate segments and having threaded therethrough conductor straps contacting the periphery of the small passages and spaced from the periphery of the larger passages, so as to connect together alternate segments of said assembled anode.

3. In an electron discharge device of the magnetron
